UNITED STATES PATENT OFFICE.

ROBERT D. PIKE, OF RICHMOND, CALIFORNIA.

RECUPERATIVE KILN.

1,207,209.

Specification of Letters Patent.

Patented Dec. 5, 1916.

Application filed June 1, 1915. Serial No. 31,342.

To all whom it may concern:

Be it known that I, ROBERT D. PIKE, a citizen of the United States, residing at Richmond, in the county of Contra Costa and 5 State of California, have invented certain new and useful Improvements in Recuperative Kilns, of which the following is a specification.

The present invention relates to kilns generally for the burning of bricks, pottery and similar articles, but the same is more particularly designed and applicable for the burning of carbons and other articles requiring a high temperature, and resides 10 more particularly in the adaptation of the bee-hive type of kiln for such purposes.

Heretofore the types of kilns commonly employed for the burning of carbons and other articles requiring high temperatures 15 are those known in the art as continuous furnaces, the objection to which resides in the fact that the material cannot be treated as independent charges.

The object of the present invention is to 20 render the bee-hive type of kiln, in which each charge may be independently treated, available for uses requiring relatively high temperatures, by increasing the thermal efficiency obtainable therein, and the invention 25 consists essentially in the construction of a down-draft kiln having a recuperator associated therewith so as to form an integral portion thereof.

In order to comprehend the invention reference should be had to the accompanying 30 sheets of drawings, wherein—

Figure 1 is a part sectional plan view of the improved kiln, showing the construction at different levels thereof. Fig. 2 is 35 a sectional elevation along the line $x-x$ of Fig. 1. Fig. 3 is a sectional elevation along the line $y-y$ of Fig. 1. Fig. 4 is a part sectional elevation along the irregular line $z-z$ of Fig. 1. Fig. 5 is an elevation, enlarged, of a detail of the recuperator construction.

Throughout the drawings, the numeral 1 is used to designate the kiln, shown as a round or bee-hive kiln for reasons herein- 40 after set forth. Said kiln 1 is here represented as built upon the surface of the ground 2, and is formed with a plurality of horizontally disposed fire openings or ports 3, preferably set at equal intervals around 45 its peripheral wall 4, said fire ports being provided with suitable fuel burners 5, and

temporary walls or fire-doors 6, and being further provided, adjacent to their inner ends, with baffle or deflector walls 7, so constructed as to direct the hot gases from the 50 burners 5 upwardly against the domed interior 4' of the roof of the kiln.

Beneath the floor 8 of the kiln 1, and set largely below the ground level 2 is the recuperator 9, which is divided by the vertical 55 central wall 10 into two substantially symmetrically disposed independent units 10' and 10², having a common outlet for the burned gases, said outlets consisting of the header 11 and the flue 12, connected with 60 any suitably constructed chimney or stack, not shown herein.

The recuperator 9 comprises the lower wing walls 13, bridged across the header 11 by the arches 14, and upon these wing 65 walls 13 are placed the vertical flues 15, constructed of stacks of hollow flanged tiles 16.

It will be seen by reference to Fig. 1 of the drawings, that the hollow tiles 16 are 70 bridged across the lower wing walls 13, so that the vertical flues 15 communicate at 75 their lower ends with the horizontally disposed flues 17 formed by the wing walls 13, Figs. 2 and 3 of the drawings, which flues in turn communicate with the header 11. 80

It will also be seen that the hollow tiles 16 forming the vertically disposed flues 15 are so placed relative to each other, that a series of channels 18 are formed between the 85 said hollow tiles 16. These channels 18 are divided into a plurality of horizontal flues 19, Figs. 2 and 3 of the drawings, by the horizontal walls 20. Said horizontal walls are shown in Fig. 5 of the drawings, as constructed of split bricks 21 resting upon the 90 flanges 22 of the hollow tiles 16. Above the stacks of hollow tiles 16 are the upper wing walls 23, which are so disposed relative to 95 each other as to form a series of vertical flues 24, which said flues communicate with the vertical flues 15, Figs. 1 and 3 of the drawings. Upon the upper wing walls 23 rests the floor 8 of the kiln, said floor being constructed with vertical passages 25 which register with the flues 24 formed by 100 the upper wing walls 23.

The recuperator, to secure the greatest thermal efficiency, is preferably rectangular in form, and divided, as before stated, by the wall 10 into two units 10' and 10², symmetrically disposed with respect to the vertical axis of the kiln. The said units 10' 110

and 10^2 are provided respectively with the air inlets 26 and 26' which are controlled by suitable dampers 27 and 27'. The air inlet 26 communicates through the chamber 28 5 with several of the lower tiers of horizontal flues 19, shown as three tiers in Fig. 2 of the drawings. At the opposite end of said recuperator unit is the chamber 29, which allows the air, after passing through the 10 three lowermost tiers of horizontal flues 19, as indicated by the arrows in Fig. 2 of the drawings, to reverse its direction and flow back through the next three tiers of horizontal flues 19 to the chamber 30, where it is 15 again reversed and passes through the uppermost four tiers of horizontal flues 19 of the recuperator unit 10' into the chamber 31.

A complete horizontal annular flue 32 is constructed in the base of the kiln wall, said 20 annular flue 32 communicating with the final recuperator chamber 31, as shown in Fig. 2 of the drawings, and also communicating through the vertical passages 33 with the fire ports 3, in proximity to the burners 25 5. The passages 33 are provided with dampers 34, operable and entirely removable through the air ports 35.

It should be noted that the companion unit 10^2 of the recuperator has its air inlet at 30 26' and therefore its outlet (not shown) into the annular flue 32 is diametrically opposite to the outlet 31 of the recuperator unit 10'. This symmetrical division of the recuperator into independent units 10' and 10^2 35 is for the purpose of insuring a free circulation of heated air in the annular flue 32, so that each burner will receive an equal supply of air. Moreover, by placing the burners at equal intervals in the periphery of the 40 kiln, an even distribution of heat within the kiln is secured.

The recuperator, as before stated, is preferably rectangular in form, but the kiln 1, for structural reasons well known in the art, 45 is circular. Moreover, the recuperator, to secure the greatest possible thermal efficiency, is set immediately beneath the floor of the said kiln, partly within the walls thereof and partly below the ground level. 50 When thus constructed there are employed the arches 37 and 38, Fig. 4 of the drawings, at the outlets of recuperator units, to secure a free passage for the heated air into the annular flue 32.

55 The operation of the kiln is as follows: Assuming that the material to be burned or baked has been placed upon the kiln floor 8, and that the kiln is cold, the air inlet dampers 27 and 27' are closed, and the slide 60 dampers 34 are removed, admitting cold air to the burners through the air ports 35. When the fires are started, the flames and hot gases, entering through the fire ports 3, are deflected upwardly by the baffle walls 7, 65 reflected from the domed roof 4' down-

wardly through the material on the kiln floor, pass through the vertical flues 15 of the recuperator units and out through the header 11 and flue 12 to the stack.

When the recuperator becomes sufficiently 70 heated to establish an ascending circulation through the air passages thereof, the dampers 27 and 27' controlling the air inlets 26 and 26' respectively are opened, and the controlling dampers 34 are inserted to close 75 the air ports 35, thereby cutting off the supply of cold air to the burners. The air now entering through the air inlets 26 and 26' of the recuperator units 10' and 10^2 , passes back and forth through the several ascending 80 stages of the horizontal passages 19 of the said recuperator units, and is distributed, at a high temperature, to the burners 5 by the annular flue 32 and the passages 33. Each of the recuperator units acts 85 correspondingly, drawing in air through the inlets 26 and 26' and discharging the same into the annular flue 32 at substantially diametrically opposite points therein. By thus using the exhaust gases to heat the incoming air, the thermal efficiency of the kiln is greatly increased over the present types of kilns in general use. In fact, the recuperative feature makes possible in a bee-hive kiln 95 the use of temperatures as high as 3000 degrees Fahr., whereas in an ordinary down-draft bee-hive kiln without the described recuperative feature, it is impracticable to secure temperatures in excess of 2500 degrees Fahr. Thus the down-draft bee-hive kiln, 100 the advantages of which are well known in the art, is rendered available for use at high temperatures, and more efficient at the ordinary temperatures at which such kilns have heretofore been used.

I am aware that various changes may be made in the described details of construction of the kiln, without in any manner changing or varying the described invention.

While the particular form of construction 110 herein described is believed to be the most practicable and efficient for the work desired, still I do not wish to be understood as limiting or confining the invention thereto.

Having thus described the invention what 115 is claimed as new and desired to be protected by Letters Patent is:—

1. The combination with a heating chamber, provided with openings in the floor thereof, of a recuperator situated immediately beneath said floor, a plurality of vertical flues in said recuperator having their upper ends in registry with the openings in the floor of said chamber, an exhaust flue in communication with the lower ends of said flues, a plurality of horizontal passages in said recuperator independent from but adjacent to said vertical flues, and chambers with which the ends of said horizontal passages register connections between said chambers 120 125 130 135

and the heating chamber so that air entering the lowermost of said horizontal passages is constrained to pass successively through a number of said horizontal passages on succeedingly higher levels before passing from the uppermost of said horizontal passages into said heating chamber.

2. The combination with a heating chamber, of a recuperator having vertical flues for conducting the exhaust gases out of said heating chamber, adjacent independent horizontal passages for conducting air into said heating chamber, and a central vertical partition dividing the recuperator into two similar independent units symmetrically disposed with respect to the vertical axis of the entire structure.

3. The combination with a heating chamber, of a recuperator situated beneath the floor thereof, said recuperator having vertical flues for conducting the exhaust gases out of said heating chamber, and adjacent independent horizontal passages for conducting air into said heating chamber, and said recuperator being divided by a central vertical partition into two similar independent units symmetrically disposed with respect to the vertical axis of the entire structure, said units having independent inlet 30 and outlet openings communicating with said horizontal air passages.

4. The combination with a heating chamber having a plurality of burners symmetrically disposed in a horizontal plane about its periphery, a horizontal annular flue within the wall of said heating chamber, and passages connecting said annular flue with said burners, of a recuperator situated beneath the floor of said heating chamber, flues 35 within the recuperator for conducting the exhaust gases away from said kiln, and passages adjacent to said flues for conducting air into said annular flue of said heating chamber, said recuperator being divided by a vertical central partition into two similar units symmetrically disposed with respect to the vertical axis of the entire structure, said units having their respective air outlets into said annular flue at diametrically opposite 45 points therein.

5. The combination with a recuperator having independent adjacent passages for relatively hot exhaust gases and relatively cold incoming air, of a heating chamber situated above the recuperator, and communicating with the recuperator, a plurality of burners symmetrically disposed in a horizontal plane about the wall of said heating chamber, a horizontal annular flue within 50 said wall, passages connecting said annular flue with said burners, air inlet ports within the kiln wall for supplying air to the burners, and slide dampers within said ports arranged to regulate the flow of air through 55 said connecting passages.

6. The combination with a heating chamber having an opening in the floor thereof, a plurality of wing walls having vertically disposed apertures therebetween communicating with the openings in the floor of the 70 heating chamber, of a recuperator having suitably disposed flues for conducting the relatively hot exhaust gases away from said chamber registering with the apertures between the wing walls, and a plurality of 75 suitably disposed confined passages arranged adjacent the exhaust flues for conducting the relatively cool unburned gases to the heating chamber.

7. The combination with a heating chamber, of a recuperator having means for leading relatively hot exhaust gases from the chamber and relatively cold incoming air thereto, a plurality of burners disposed about the wall of the chamber, a flue around 85 the recuperator and passages connecting the flue with the chamber, air ports leading to the connecting passages and dampers arranged within said ports, substantially as 90 described.

8. The combination with a heating chamber having a plurality of wing walls with apertures therebetween, of a recuperator provided with suitably disposed passages for conducting the hot exhaust gases from 95 the chamber in registry with the vertically disposed apertures between the wing walls below the recuperator and an independent inlet passage adjacent the exhaust passage for conducting relatively cool fluid in the 100 tortuous direction into the heating chamber.

9. The combination of a heating chamber, provided with openings in the floor thereof, of a recuperator disposed within the said chamber, a plurality of vertically disposed flues in the recuperator having their upper ends in registry with the openings in the floor of the heating chamber, a plurality of wing walls having therebetween passages arranged at the lower end of said vertical flues and communicating therewith for leading the exhaust gases from the recuperator, and independent inlet passages adjacent the 105 exhaust gases flues in said recuperator for supplying relatively cool air to the heating 110 chamber.

10. The combination with a heating chamber provided with openings in the floor thereof, a recuperator situated beneath said chamber, a plurality of vertically disposed flues in said recuperator having their uppers in registry with the openings in the floor of the heating chamber, a plurality of wing walls, having passages therebetween arranged at the lower end of said vertical flues and in communication therewith for leading the exhaust gases from the recuperator, a plurality of horizontal passages 120 in the recuperator arranged adjacent the vertical flues, but independent thereof, and 125 130

chambers with which the ends of said horizontal passages register so that air entering the lowermost of said horizontal passages is caused to pass upwardly in a substantially zig zag direction before entering the heating chamber.

11. The combination with a heating chamber of a recuperator having flues for conducting the exhaust gases out of said chamber, adjacent flues for conducting air into said heating chamber, and a partition dividing the recuperator into two independent units symmetrically disposed with respect to the vertical axis of the entire 15 structure.

12. The combination with a heating chamber, of a recuperator having flues for conducting exhaust gases from the chamber, adjacent flues for conducting air to the heating chamber, and a partition dividing the recuperator into independent units, substantially as described. 20

In testimony whereof I have signed my name to this specification in the presence of two subscribing witnesses.
